UNITED STATES PATENT OFFICE

2,630,964

COMPRESSOR MOUNTING

Owen H. Scheldorf, North East, Pa., assignor to
 General Electric Company, a corporation of
 New York

Application December 14, 1949, Serial No. 132,881

7 Claims. (Cl. 230—58)

1

My invention relates to motor-compressor assemblies and more particularly to arrangements for mounting such assemblies within an enclosing casing.

It is an object of my invention to provide a motor-compressor assembly including an improved arrangement for maintaining a uniform air gap between the stator and the rotor of the motor.

Further objects and advantages of my invention will become apparent as the following description proceeds and the features of novelty which characterize my invention will be pointed out with particularity in the claims annexed to and forming part of this specification.

For a better understanding of my invention reference may be had to the accompanying drawing in which Fig. 1 is an end elevation view partly in section of a motor-compressor assembly embodying my invention; Fig. 2 is a side elevation view taken along the line 2—2 in Fig. 1; Fig. 3 is an enlarged view showing a detail of my invention; Fig. 4 shows the construction of Fig. 3 in another stage of the assembly; and Fig. 5 illustrates a modified form of my invention.

In carrying out the objects of my invention a rotor-compressor assembly is positioned within an enclosing casing with the rotor in proper spaced relationship to the stator. The enclosing casing and the frame of the compressor are shaped to receive spaced elements which are forced into grooves in the casing and the frame to fix the rotor-compressor assembly in position.

Referring to Figs. 1 and 2 there is shown an enclosing casing or housing 1 of hollow cylindrical shape. Within the casing is arranged a motor-compressor unit including a motor 2 and a compressor 3. For purposes of illustration an enclosed motor-compressor unit for use as refrigerating apparatus is illustrated, but motor-compressor units employed for other purposes may equally well be constructed in accordance with my invention. In the form illustrated the ends of the casing 1 are closed by end plates, one such end plate being shown at 4. Compressed refrigerant is discharged from the compressor 3 through an exhaust muffler 5 and a conduit 6 to the condenser (not shown) of the refrigerating system and vaporized refrigerant is returned from the evaporator (not shown) to the interior of the casing 1 through the conduit 7. This vaporized refrigerant passes from the casing through an intake muffler 8 to the compressor.

The motor 2 includes a stator 9 and a rotor 10 mounted to rotate within the stator. The stator 55

2

9 includes a laminated core structure 11 and windings 12 disposed within slots in the core structure. The stator is secured in fixed position within the casing 1.

5 The compressor 3 includes a frame 13 which is shaped to provide a boss 14 having an opening therein providing a bearing surface for the drive shaft 15 which connects the rotor and the stator. The rotor is supported entirely by the frame of the compressor through the shaft 15, forming a rotor-compressor assembly.

In order to position this rotor-compressor assembly longitudinally within the casing, the casing is shaped to provide a shoulder 16. The shoulder 16 may be formed in any suitable manner, for example, by rolling a recess in the wall of the casing to force the wall inwardly at the shoulder 16. The frame 13 of the compressor includes a portion 17 which is arranged to abut the shoulder 16 affording a positive longitudinal positioning for the rotor-compressor assembly.

For satisfactory low noise operation it is necessary that a uniform gap between the rotor and the stator be maintained throughout the periphery of the rotor. By my invention the rotor-compressor assembly is easily and positively mounted so that this uniform air gap is provided.

25 The casing 1 is provided along its interior surface with an annular groove 18 which is spaced longitudinally from the shoulder 16. As is most clearly illustrated in Figs. 3 and 4, the frame portion 17 is similarly provided with an annular groove 19. The groove 19 is formed so that in the assembled position of the compressor, the grooves 18 and 19 are in aligned relationship.

30 During the assembly operation the rotor-compressor assembly and the casing are held in any suitable fixture for temporarily maintaining the proper uniform air gap between the rotor and the stator. In order to fix the parts permanently in this position a plurality of tubular elements or keys 20 are inserted between the frame portion 17 and the casing 1 at intervals about the circumference. In the form illustrated four such keys are used, the keys being equally spaced at 90° intervals about the casing. The frame portion 17 is shaped to provide a recess 21 for receiving the keys 20.

35 With the keys disposed at proper intervals a force is applied to each of the keys by a pressing tool 22. This force squeezes and flattens the keys 20 into the laterally elongated flattened shape shown in Fig. 4. As the keys are flattened the sides of the keys are forced into the grooves 18 and 19 forming a support for the rotor-compressor assembly and radially positioning

this assembly so that the uniform air gap temporarily maintained by the fixture is permanently fixed.

It can be seen that the construction described above compensates for slight variations which may occur in manufacturing and further that the need for carefully machined surfaces is minimized since the periphery 23 of the frame portion 17 is spaced by the keys 20 from the inner wall of the casing.

In Fig. 5 there is illustrated a modified form of my invention which differs from that described above only in that each of the keys 24 is of hollow triangular cross section. One side of the triangular key 24 is disposed against a flat face 25 of the frame portion and a force is exerted against an apex 26 of the key by the pressing tool 22. The force exerted by the tool 22 flattens the key 23 into substantially the shape shown in Fig. 4, forcing the key laterally into the grooves 18 and 19 in the manner described above.

While I have shown and described specific embodiments of my invention as applied to an enclosed refrigerating motor-compressor unit, other applications will occur to those skilled in the art, and I intend to cover by the appended claims all modifications within the spirit and scope of my invention.

What I claim as new and desire to secure by Letters Patent of the United States is:

1. A motor-compressor assembly comprising a casing having a shoulder on the interior surface thereof, said casing having an annular groove therein spaced from said shoulder, a motor-compressor unit having a frame portion abutting said shoulder, said frame having an annular groove therein concentric with said first-mentioned groove, and a plurality of elements each engaging both of said grooves and having a pressed fit therewith to hold said motor-compressor unit in fixed position with said casing.

2. A motor-compressor assembly comprising a casing having a shoulder on the interior surface thereof, said casing having an annular groove therein spaced from said shoulder, a motor-compressor unit having a frame portion abutting said shoulder, said frame having an annular groove therein concentric with said first-mentioned groove, and a plurality of flattened hollow elements each engaging both of said grooves to hold said motor-compressor unit in fixed position with said casing.

3. A motor-compressor assembly comprising a hollow cylindrical casing having a shoulder on the interior surface thereof, said casing having an annular groove therein spaced from said shoulder, a motor-compressor unit having a frame portion abutting said shoulder, said frame having an annular groove therein concentric with said first-mentioned groove and a plurality of flattened hollow elements equally spaced about the internal periphery of said casing, each of said elements engaging both of said grooves to hold said motor-compressor unit in fixed position within said casing.

4. A motor-compressor assembly comprising a casing having a shoulder on the interior surface thereof, a stator mounted within said casing, a rotor-compressor assembly including a frame portion arranged within said casing, said frame portion abutting said shoulder, and means for maintaining a uniform air gap between the

rotor and said stator, said means comprising an annular groove in said casing spaced from said shoulder, an annular groove in said frame portion concentric with said first-mentioned groove, and a plurality of flattened hollow elements engaging both of said grooves.

5. In a motor-compressor assembly comprising a casing having a stator and a rotor-compressor unit mounted therein, the compressor of said rotor-compressor unit including a frame portion, the method of positioning the rotor within said stator with a uniform air gap which comprises providing said casing with an internal shoulder, forming an annular groove in said casing spaced from said shoulder, forming a complementary groove in said frame portion of said compressor, holding said rotor in properly spaced relationship with said stator, placing a plurality of hollow elements in spaced relationship between said frame portion and said casing, and exerting a force on said elements to flatten said elements and to force said elements into engagement with both of said grooves.

6. In a motor-compressor assembly comprising a casing having a stator and a rotor-compressor unit mounted therein, the compressor of said rotor-compressor unit including a frame portion, the method of positioning the rotor within said stator with a uniform air gap which comprises providing said casing with an internal shoulder, forming an annular groove in said casing spaced from said shoulder, forming a complementary groove in said frame portion of said compressor, holding said rotor in properly spaced relationship with said stator, placing a plurality of hollow tubular elements in spaced relationship between said frame portion and said casing, and exerting a force on said elements to flatten said elements and to force said elements into engagement with both of said grooves.

7. In a motor-compressor assembly comprising a casing having a stator and a rotor-compressor unit mounted therein, the compressor of said rotor-compressor unit including a frame portion, the method of positioning the rotor within said stator with a uniform air gap which comprises providing said casing with an internal shoulder, forming an annular groove in said casing spaced from said shoulder, forming a complementary groove in said frame portion of said compressor, holding said rotor in properly spaced relationship with said stator, placing a plurality of hollow elements of triangular cross section in spaced relationship between said frame portion and said casing, and exerting a force on said elements to flatten said elements and to force said elements into engagement with both of said grooves.
